[57] CLAIM

The ornamental design of a combined floor lamp, adjustable reading light on swing arm, and table, as shown and described.

DESCRIPTION

FIG. 1 is a perspective view of a combined floor lamp, adjustable reading light on swing arm, and table showing my new design;

FIG. 2 is a front view thereof;

FIG. 3 is the right side view thereof;

FIG. 4 is the left side view thereof;

FIG. 5 is a top plan view thereof; and,

FIG. 6 is a bottom plan view thereof.

The appearance of the article embodying the claimed design, may be varied by the pivotal movement of the lamp head of either or both of the floor lamps and the reading light as shown by the broken lines and arrows on the drawings.
